US00D741334S

(12) **United States Design Patent**
Hillenmayer et al.

(10) **Patent No.:** US D741,334 S
(45) **Date of Patent:** ** Oct. 20, 2015

(54) **DOCKING STATION FOR TELEPHONE AND FLAT COMPUTER**

(71) Applicants: **Stefan Hillenmayer**, Munich (DE);
Patrick Treder, Munich (DE)

(72) Inventors: **Stefan Hillenmayer**, Munich (DE);
Patrick Treder, Munich (DE)

(73) Assignee: **Unify GmbH & Co. KG**, Munich (DE)

(***) Term: **14 Years**

(21) Appl. No.: **29/480,604**

(22) Filed: **Jan. 28, 2014**

(30) **Foreign Application Priority Data**

Aug. 1, 2013 (DE) 40 2013 003 523

(57) **CLAIM**

The ornamental design for a docking station for telephone and flat computer, as shown and described.

DESCRIPTION

FIG. 1 is front perspective view of our docking station for telephone and flat computer;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

1 Claim, 7 Drawing Sheets
